ELECTRIC SAFETY SWITCH

Filed March 18, 1927

1961

FIG. C. 12

Fig. 4.

William C. Davis Jr. Inventor

By Robert Robt

Attorney:

UNITED STATES PATENT OFFICE.

WILLIAM C. DAVIS, JR., OF JASPER, ALABAMA.

ELECTRIC SAFETY SWITCH.

Application filed March 18, 1927. Serial No. 176,477.

This invention relates to an electric safety switch, and particularly to a construction in which the switch point is locked in closed position and electrically released therefrom by 5 a circuit contact at a removed point of control.

In the electric control of safety switches I have found it very desirable to employ an electrically actuated latch or lock and to 10 effect the shifting of the switch point by supplemental means after the release of the latch. To accomplish this result I provide a latch member disposed to positively engage the movable switch point and adapted to be 15 electrically released therefrom by a magnet member so as to leave the point free for opening movement which may be accomplished by a spring or other devices.

In such a construction it is further desirable 20 that when the switch point is forced to closed position by engagement with a wheel flange, the latch should automatically engage and hold the point independent of any electrical action. A construction is thus provided by which the momentary energizing of 25 the controlling magnet effects a release of the switch point and the further movements thereof are automatically effected so that it is not necessary to depend upon electric devices for shifting the point and restoring it 30 to closed position.

The invention has for an object to provide a novel and improved construction of electric safety switch in which a movable member is engaged by a latch by which it is held 35 in closed position and such latch is adapted to be actuated by a magnet for releasing its engagement with the movable switch member or point.

40 A further object of the invention is to provide tension means by which the switch point will be automatically shifted into open position and the latch restored to its engaging position with said point when closed.

45 Another object of the invention is to provide a simple and efficient construction of electrically actuated latch adapted for application to a safety switch to be controlled by a train device adapted to establish circuit to 50 the actuating magnet of the switch.

Other and further objects and advantages of the invention will be hereinafter set forth and the novel features thereof defined by the appended claims.

55 In the accompanying drawing:

Figure 1 is a plan showing the switch applied;

Figure 2 is a detail perspective of the switch point and latch;

Figure 3 is a detail section of the point 60 in closed position; and

Figure 4 is a modified form of the invention.

Like reference characters designate corresponding parts throughout the several figures of the drawing.

This construction of safety switch is adapted for various applications but is particularly designed for use in connection with safety switch systems such as shown in my 70 copending application filed of even date herewith. In the application of the invention shown in Figure 1 the numeral 10 designates the main line rails and 11 the rails or tracks of a siding having switch connection therewith. This switch comprises a movable point 12 pivotally mounted at 13 and tensioned into open position by a spring 14 or other suitable means. The switch point 12 is provided with an aperture 15 the 75 rear wall 16 of which is adapted to cooperate with a latch 17 which may be of hooked construction as shown. This latch is pivotally mounted at 18 upon a suitable support and formed with an armature face 19 which 80 cooperates with an electro-magnet 20 having circuit connections 21 extending therefrom. These connections are intended to cooperate 85 with a third rail and the track rails as shown in my application aforesaid and circuit is 90 established by a train controlled device as shown in said application.

In order to throw the latch into engaging position with the switch point when the magnet is not energized, a spring 22 may 95 be extended therefrom to a fixed point and the various parts of the latch mechanism are adapted to be enclosed by a suitable casing as indicated at 23 in Figure 1 by which they are protected from dirt and moisture to insure 100 their continued efficient operation.

In Figure 4 a modified form of the invention is shown in which the switch point 12 is positively actuated into open position through the controlling magnet for the 105 latch and there held by spring 14. In this form of the invention the latch 25 is provided with a hooked end 26 engaging the wall 16 of the opening 15 in the point 12 and is pivotally mounted at 27 from which 110

point a crank arm 28 carries a pusher bar 29 slidably mounted thereon by means of the slot 30 operating upon the pin 31 of the crank arm 28. The inner end of the push bar 29 is formed with a lateral arm 32 from which a tension spring 33 extends to the crank arm 28. The opposite end of the bar 29 passes through a guide 34 and engages the body of the switch point 12. For the purpose of actuating the latch to release the same a magnet 35 is provided and the solenoid 36 therefrom has a loose pivotal connection with the latch at 37 to provide for the arcuate movement of the latch and the rectilinear movement of the solenoid. The latch is normally tensioned into engaging position with the point by a spring member 38 surrounding the solenoid and extending between the magnet and a collar 39 on the solenoid. This solenoid is suitably guided in its movement by means of a rod 40 as shown in Figure 4.

In the operation of this form of the invention the initial movement of the solenoid releases the latch and the crank arm thereof has an idle movement upon the pusher bar until such release is effected and thereafter actuates the pusher bar to positively throw the switch. In the closing of the switch by contact with the wheel flange of a train the bar is first actuated and by its pressure upon the crank arm of the latch insures a positive actuation thereof into engagement with the point in the event that the spring provided for that purpose is not sufficient. In both forms of the invention the hooked end of the latch has an inclined face 41 which engages the wall 16 of the aperture in the switch point and forces the latch away from said wall sufficiently to permit the closing of the point.

The operation of the invention will be apparent from the foregoing description from which it will be seen that the switch point is normally held in locked position and cannot be released therefrom except through a circuit established in the magnet controlling one movement of the latch, and after such release the switch point is thrown to its open position by supplemental means. Under such a construction it is only necessary to provide sufficient current to actuate the latch as its releasing movement and the opening of the switch may be effected by other means. This avoids the necessity of any complicated electrical connections for operating the switch point and provides a simple, efficient and economically constructed controlling device for the switch.

While the details of construction have been shown and described, the invention is not confined thereto as changes and alterations may be made therein within the spirit

of the invention as defined by the following claims.

Having thus described my invention, what I claim as new and desire to secure by Letters Patent of the United States, is:—

1. In an electric safety switch, a movable rail member, a latch disposed to directly engage said member, and an electrically actuated magnet arranged to release said latch.

2. In an electric safety switch, a movable rail member, a latch disposed to directly engage said member, an electrically actuated magnet associated with the latch and rail member to release said latch, and tension means for shifting said movable member when released by said magnet.

3. In an electric safety switch, a movable rail member, a latch disposed to directly engage said member, an electrically actuated magnet arranged to release said latch, and tension means connected to restore said latch to engaging position when the magnet is not energized to permit its automatic engagement with the rail member.

4. In an electric safety switch, a movable switch point, a pivoted latch adapted to directly engage and retain the same in closed position, an electrically energized magnet device cooperating with said latch to release the same from engagement with said point, and tension means extending from said latch to restore the same to engaging position.

5. In an electric safety switch, a movable switch point, a pivoted latch adapted to directly engage and retain the same in closed position, an electrically energized magnet device cooperating with said latch to release the same from engagement with said point, tension means extending from said latch to restore the same to engaging position with said point, and a tension spring extending from said switch point to automatically open the same when released.

6. In an electric safety switch, a pivoted switch point having an aperture therein, a latch member having a hooked end adapted to extend through said aperture and engage a wall thereof, a magnetically attracted member carried by said latch, and a magnet cooperating with said member to shift the latch to released position.

7. In an electric safety switch, a pivoted switch point having an aperture therethrough, a pivoted latch having a hooked head adapted to engage a wall of said aperture and an inclined outer face adapted to be engaged by said point, a tension spring extending from said latch to a fixed point for restoring the same, and a magnet member disposed to attract and shift said latch to a released position.

In testimony whereof I affix my signature.
WILLIAM C. DAVIS, JR.
